UNITED STATES PATENT OFFICE

HARRY W. PROTZELLER, OF EAST CHICAGO, INDIANA, ASSIGNOR TO O. F. JORDAN COMPANY, OF EAST CHICAGO, INDIANA, A CORPORATION OF INDIANA

RAIL JOINT OILER

Application filed February 23, 1927. Serial No. 170,293.

This invention relates to improvements in rail joint oilers and it consists of the matters hereinafter described and more particularly pointed out in the appended claims.

The rail joint oiler illustrated herein is of the kind embodying a vehicle intended for travel upon a railroad track which vehicle includes an electro-magnetic valve for controlling the passage of fluid to associated spray nozzles adapted to be swung about an axis into and out of operative position with respect to the rails; the operation of the valve in turn being controlled by a joint plate contactor also swingable toward and away from the rail and against which it normally has a rolling engagement to energize and de-energize the valve in the passing of each rail joint.

The primary object of the invention is to provide an improved mechanism for simultaneously moving both the nozzle and contactor into and out of operative position with respect to the rail.

Another object of the invention is to provide an improved mounting for the contactor whereby that portion of the contactor having a rolling engagement upon the rail may be accurately and easily adjusted for rails of different heights.

A further object of the invention is to provide an improved mounting of the nozzles on the valve casing whereby the angular position of the nozzle when in operative position may be determined to regulate the area of contact of the spray upon the rail joints.

Still another object of the invention is to provide an improved mounting of the valve upon the vehicle so that it may be adjusted laterally to bring its axis into the plane of the rail and at the same time evenly space the nozzles on each side of the rail.

These objects of the invention as well as the many advantages thereof, will more fully appear as I proceed with my specification.

In the drawings:

Fig. 1 is a view in side elevation of a rail joint oiler embodying my invention.

Fig. 2 is a fragmentary view in side elevation on an enlarged scale of those parts of the rail joint oiler located between the sup-

porting wheels thereof, some of said parts being disposed in a position different from that shown in Fig. 1.

Fig. 3 is a transverse vertical sectional view through the same on a further enlarged scale, 55 the plane of the section being indicated by the line 3—3 of Fig. 1 and a portion of the valve casing is shown as broken away to more clearly disclose the interior construction thereof.

Fig. 4 is a detail view in side elevation showing the manner of mounting the nozzle head on the valve casing and which will be more fully referred to later.

Fig. 5 is a detail transverse vertical sectional view on a further enlarged scale, 65 the plane of the section being indicated by the line 5—5 of Fig. 1.

Fig. 6 is a detail transverse vertical sectional view through a portion of the rail joint oiler as taken on the line 6—6 of Fig. 1 70 and shows the manner of adjusting the contactor supporting member.

Figure 7 is a diagrammatic view showing the electrical circuit between the electro-magnetic valve and associated contactor and which will be more fully described later.

Referring now in detail to that embodiment of the invention illustrated in the accompanying drawings, 1 indicates as a whole the frame of a rail joint oiler mounted on front and rear axles 2 and 3 respectively, each of which is provided with a pair of wheels 4—4 to run on the rails 5 of a railroad track. The rail lengths in each rail of the tracks are 80 connected together by inner and outer joint plates and bolts 6 in the manner well known. The wheeled frame thus generally described forms the vehicle of a rail joint oiler which is preferably self-propelled, having a suitable power plant operatively connected to the rear axle but not herein shown.

The frame of the vehicle is rectangular in plan and embodies side sills 7 and transverse end sills 8—8, the side sills being duplex in their nature and each comprising a pair of laterally spaced edgewise disposed inner and outer channels 7a and 7b respectively, with the flanges thereof facing toward each other as best shown in Figs. 3 and 5.

Fixed to and projecting laterally from each side sill is a plurality of brackets 9 upon which is supported a casing or tank 10 adapted to contain the fluid to be sprayed, preferably a low-grade, slow evaporating oil.

11 indicates as a whole the casing of an electro-magnetic valve mounted upon and projecting laterally from the outer side sill members 7b at a point midway between the axles. Said casing includes an upright back flange 12 secured to the web of the sill member 7b by means of bolts and nuts 13, one near each end of the back flange. Carried by each end of the back flange, vertically above and below each attaching bolt and nut 13 are set screws 14, each of which are threaded through the flange to engage the web of the sill member 7a. On each set screw is threaded a locking nut 15. By manipulating the set screws and nuts 14 and 15 after loosening the bolts and nuts 13, the casing may be shifted laterally toward or away from the said sill member to accurately position the vertical axis of the valve casing in the vertical plane of the rail 5. After this adjustment has been made, the set screws and bolts are tightened up as well as the bolts and nuts 13 whereby the valve casing is secured in the desired position. Thus inaccuracies in the various parts may be readily compensated for.

The valve casing comprises an open bottom casing member 16 and an open top casing member 17 both of which have coacting radial flanges. Interposed between said flanges is an annular plate 18, and said flanges and plate are all secured together by suitable bolts 19 only one of which appears in Fig. 3. Said plate which has a centrally disposed apertured flange 18a therein divides the casing as a whole into top and bottom chambers 20 and 21 respectively, the former being a magnetic coil chamber and the latter being a pressure fluid chamber. Fluid under pressure is admitted to said last mentioned chamber by means of a conduit 22 leading from a pressure generating means supplied with fluid from the tank 10. As the pressure generating means forms no particular part of the present invention it is referred to only generally and is not herein illustrated. In the casing member 17 and surrounding the chamber 21 therein is an annular heating chamber 23 into which the exhaust gases of the power plant for propelling the vehicle is conducted by a pipe 24 opening into said chamber at the rear above the pipe 22. Said chamber opens at the front to the atmosphere for the discharge of said exhaust gases which act to heat up the fluid in the chamber 21 and thus increase its fluidity.

Depending from the bottom of the casing member 17 is a boss 25 having a taper-bottomed recess 26 therein which opens into the

chamber 21 and extending transversely through said boss below said recess is a horizontal passageway 27 connected to said recess by an axially disposed port 28. In the chamber 20 is located an annular magnetic coil 29 resting at its bottom upon the plate 18 and suitably insulated from both said casing member and plate. 30 indicates the normally fixed but adjustable core of the electro-magnetic valve as a whole which is threaded through the top wall of the casing member 16 to extend a suitable distance down into the interior of said annular coil. 31 indicates the movable core of the valve which is guided in its movement by the apertured flange 18a of the plate 18. Said core is in the form of a cylinder of magnetic material and threaded axially into the bottom end thereof is the top end of a stem 32. To the bottom end of said stem is fixed a block 33 in which is carried a valve member 34 in the form of a steel ball adapted to seat on the tapered bottom of the recess 26 about the port 28 to control the passage of the fluid from the chamber 21 to the lateral passageway 27. When the coil 29 is energized, it attracts the core 31 to lift the ball valve off the seat so that fluid under pressure enters to the passageway 27 and when said coil is de-energized, the core 31 descends and the ball valve seats itself and closes off the flow of fluid to said passageway.

Associated with said valve as a whole is a duplex spray nozzle head 35 comprising laterally spaced branch pipes 36-36 connected at a point between their ends by a transverse pipe 37 and a transverse bar 38 below the same. The pipe 37 equalizes the pressure in the branch pipes while the purpose of the bar 38 will later appear. To the top end of each branch pipe is secured a swing joint elbow fitting 39 the nipples 40-40 of which are threaded into the ends of the transverse passage 27. This connection is such that it permits the nozzle head as a whole to be swung about an axis coincident with that of said passageway 27. The bottom end of each branch pipe 36 is bent outwardly and each end has a nozzle opening 41 facing the rail and associated with each opening is a valve stem 42. The valve stem and nozzle opening are so disposed that when the nozzle head is in its operative position with respect to a rail a conical spray of the fluid under pressure is delivered upon the joint plates of the track only and not upon the tread surface of the head of the rail, as is apparent from an inspection of Fig. 3.

Means are provided to manually swing the nozzle head about its connection with the boss 25 and such means are as follows: Secured to the outer sill member 7b are front and rear pairs of brackets 43-44, each bracket being of the same construction. Each bracket includes an upright plate 45 fixed to the outer face of the sill member 7b and a

horizontally disposed arm 46 suitably webbed to said plate for strength. Said arm is of such a length that its outer end projects a suitable distance outwardly beyond the sill member 7b while its inner end extends a less distance inwardly beyond the sill member 7b. In the outer end of each arm is a longitudinally extending hole 47 and depending from said outer end is an ear 48 in which is a transverse hole 49. The inner end of said arm has top and bottom ears 50—51 respectively and in the ear 51 is a hole 52 in line with the hole 49 in the ear 48. In said holes 49 and 52 is journaled a transverse rock shaft 53. The top ear 50 of said bracket has a hole 54 therein in which is fixed a stub shaft 55 arranged vertically above the shaft 53. On the inner end of the shaft 53 is fixed a pinion 56 which meshes with a segmental gear 57 journaled on the stub shaft 55. Said segmental gear is provided with a hand lever 58 for manual operation and on the sill member 7b is a notched quadrant 59 to coact with a latch or detent 60 on the lever (see Fig. 2), whereby the lever may be locked in the desired position. On the shaft 53 is a sprocket 61 fixed thereto by a set screw 62 the sprocket being arranged on said shaft in the plane of the rail 5. A sprocket chain 63 is fixed at its top end to said sprocket and at its bottom end to the cross bar 38 of the nozzle head. On the front side of the boss 25 is mounted a depending bracket 25a and secured to the front end of said bracket and to said nozzle head cross bar 38 is a pair of contractile springs 35a which normally urge the nozzle head into its operative position. Threaded through said bracket between said springs is a longitudinally extending set screw 25b adapted to be engaged by the cross pipe 37 of the nozzle head under the action of the springs 35a. By screwing said set screw in or out the angularity of the nozzle head when in its operative position may be determined, said set screw acting as an adjustable stop shoulder therefor. This feature is important because by it, the angularity of said nozzle head may be determined to properly gauge the position of the nozzle openings with respect to rails of different heights. It is apparent that when the lever 58 is moved rearwardly the sprocket 61 and shaft 53 are rocked counter clockwise to wind up the chain and thus lift the nozzle head 35 into its inoperative position with respect to the rail against the action of the springs 35a, the detent 60 entering the proper notch in the quadrant to hold said nozzle head in this position as best shown in Fig. 2. When the detent is released the springs 35a act to swing the nozzle head into its operative position which is defined or limited by the engagement of the cross pipe 37 with the screw 25b. It is pointed out at this time that by loosening the set screw 62 which fixes the sprocket 61 on the shaft 53 the angular rela-

tion between the sprocket 61 and the rock shaft 53 may be changed by turning the sprocket on the shaft and then locking it to the shaft by the set screw 62. Thus the position of the actuating lever need in no manner be changed with respect to the angularity of the nozzle head and this feature is advantageous because said lever is also adapted to actuate another mechanism as will soon appear. 75

Means are provided for automatically making and breaking the circuit to the electro-magnetic valve each time a rail joint is approached and passed whereby the passage of fluid under pressure to the nozzle head is controlled and such means is as follows: In the holes 47 in the outer ends of the arms 46 of the front pair of brackets 43 is journaled a rock shaft 65 suitably held in said arm ends against endwise movement. Capable of being securely fixed to said shaft is bifurcated plate 66 which includes a sleeve 67 embracing a part of said shaft and adapted to be locked thereto by a set screw 68, and two spaced plate-like parts 69—69 each having a pair of slots 70—70 therein extending at a right angle to said sleeve. Interposed between said plate like parts 69—69 is one end of a flat plate like arm 71, bolts 72 with suitable nuts thereon passing through the slots 70—70 and through suitable holes in said end of the plate like arms. The other end of said arm carries a right angle flange 73 and journaled on an axis parallel with said flat plate like arm is a roller 74 adapted for a rolling engagement along the inner top corner of the head of a rail when said plate-like arm is in its operative position. Mounted on said flange is a suitable make and break switch including a fixed contact 73a adapted to be engaged by a yieldable finger 75 best shown in Fig. 2. Said contact and finger are indicated in the diagram in Fig. 7 and in said figure, one side of a generator 81 and battery 82 are grounded while the other sides thereof are connected by a conductor 83 in which is interposed an ammeter 84. One terminal of each coil 29 is connected by a conductor 85 to an associated fixed contact 73a while the other terminals of said coils are connected by a conductor 86 and a suitable switch 87 is interposed between said conductors 83 and 86. When said roller 74 engages the rail as before mentioned, said finger projects below the head of the rail and into a position to engage the inner joint plate. Thus when a rail joint is approached the finger engages the advancing end of the inner plate and is actuated thereby to close the switch and likewise close the circuit to the electro-magnetic valve which operates to energize said coil as before described. As the joint is passed the finger 75 slips off the trailing end of said plate to open the switch breaking the circuit to the coil and de-energizing the same. Should a groove 130

wear in the periphery of the wheel which would change the relative position of the contact or finger 75 or should a section of track be encountered wherein the rails are smaller in cross section and the position of said finger 5 need therefore be readjusted, it is only necessary to loosen the bolts 72 of the member 66 and lengthen or shorten the arm 75. By either lengthening or shortening the arm 75 a new area of the roller is brought into engagement with the rail or the relative desired position of the contact finger may be readily brought about. Of course, after making this adjustment the bolts 72 are again tightened up. By loosening the set screw 68 and moving the member 66 one way or the other on the shaft, the timing of the making and breaking of the circuit to the valve with reference to when it opens and closes may be determined whereby the "length" of spraying on each 10 joint may be governed. Thus where some railroads desire to spray three inches behind and three inches in front of each joint, this may be provided for and when it is desired that the spray be applied to the joint plates 20 only and not behind or in front of the same this too, may be provided for.

Means are provided for swinging the contactor arm about the shaft 65 as an axis and 30 preferably the same is operatively connected up with the lever 58 so that when the nozzles are swung into their inoperative position the contactor is likewise swung into its inoperative position away from the rail as best shown 35 in Fig. 2. To this end I provide the following. In the hole 54 of the top arm 50 of the bracket 43 just forward of the electro-magnetic valve is fixed a stub shaft 76 carrying a grooved segment 77. Secured to one end of 40 said segment is one end of a chain 78 which extends around the groove of the segment and is then attached at its other end to a web 79 on the rear side of the contactor arm 71 as best shown in Fig. 6. By this arrangement 45 of chain and segment, leverage on the chain is always the same as the tangent of the segment remains constant. It is preferably desirable to connect the segment to the lever 58 so that it may be swung into inoperative position 50 simultaneously with the nozzle head 35. To this end I find it convenient to interpose a link 80 between the lever 58 and segment 77 as best shown in Fig. 2. In this manner upon actuating the lever 58 the nozzle head 55 35 and contactor arm 71 may be simultaneously swung upwardly into inoperative position and held therein by the detent 60. When the detent is released the springs 35a act to return 60 said parts to their operative position with respect to the rail as before described.

As before mentioned, the brackets of both pairs of brackets 43 and 44 are all alike and from an inspection of Fig. 1 it appears as if the rearmost bracket of the pair 44 has no 65 function. It is pointed out that on some rail-

roads there is no provision for turning such an oiler around so that it may run forwardly upon the other track when the end of the road has been reached. To run the oiler backward is possible but not only would the nozzle be 70 facing in the wrong direction but the contactor would be to the rear of the nozzle so that the oiler could not operate as intended. Under such conditions, the bracket 25a would be removed from the front side of the boss 75 25 and replaced upon the opposite side of the same and then hooked up with the nozzle head. The shaft 65 would be removed from the pair of brackets 43 and replaced in the brackets 44 and the shaft 53 would likewise 80 be removed from the arms 48 and 51 of one bracket 44 and replaced in the same position in that bracket 43 adjacent the magnetic valve. The contactor on one side of the machine would be changed for that on the other 85 side so that the contactor finger 75 would face in the proper direction. The lever 58 and segment 77 would then be removed and replaced in reversed position. Thus when the oiler is travelling upon the second track of 90 the railroad, with the rear end of the oiler foremost, the positions of the various operative parts relative to the direction of travel of the oiler as a whole will be the same as before. This change in the relative position of 95 the parts may be readily made so that even though no turntable is found at the end of a run, the oiler may be used upon another track and ran rearwardly thereon. Thus a great 100 dal of time and inconvenience is saved when such a condition is met with.

My improved rail joint oiler is positive in 105 operation, and is readily adjustable to meet all contingencies. It comprises but a few parts which are strong and rigid and which are not only easily assembled but are readily accessible for inspection or repair.

While in describing my invention, I have referred in detail to the general form as well 110 as the arrangement of the various parts thereof, the same is to be considered as by way of illustration only so that I do not wish to be limited thereto except as may be pointed out in the appended claims.

I claim as my invention:

1. A rail joint oiler embodying therein a 115 frame, a valve casing laterally supported thereon, a nozzle head including laterally spaced nozzle members operatively connected to said casing, and means providing for a lateral adjustment of the valve casing toward and away from said frame to locate the nozzle members with respect to the vertical median plane of the rail.

2. A rail joint oiler embodying therein, a 120 frame, a valve casing at the side of said frame, a nozzle head including laterally spaced nozzle members swingably secured to the valve casing, and means providing a bolted connection of said casing on said frame and 125

capable of a lateral adjustment to locate the nozzle member with respect to the vertical median plane of the rail.

3. A rail joint oiler embodying therein, a frame member, a valve casing including a back flange member, spaced laterally from the frame, a nozzle head including laterally spaced nozzle members swingably supported on the valve casing, bolts connecting the back flange member to the frame member and set 10 screws threaded in one member to engage the other and providing a lateral adjustment of the valve casing with respect to said frame to locate the nozzle members with respect to the vertical median plane of the rail.

15 4. A rail joint oiler embodying therein, a frame member, a valve casing supported thereon, a nozzle head mounted on the valve casing for a swinging movement longitudinally of the frame member and including 20 nozzle members disposed one on each side of the rail, means for swinging said nozzle into operative position, a rock shaft extending transversely of the frame member and a flexible member connecting said rock shaft 25 and nozzle head for swinging it into its inoperative position.

30 5. A rail joint oiler embodying therein, a frame member, a valve casing supported thereon, a nozzle head mounted on the valve casing for a swinging movement in the plane 35 of the frame member, means for swinging said nozzle into operative position, a rock shaft extending transversely of the frame member, means mounted on the frame for 40 rocking the shaft, a circular member rotative with the rock shaft and a flexible member connected at one end to said nozzle head and at the other end to said circular member to swing 45 said nozzle head into inoperative position upon movement of the rock shaft in one direction.

50 6. A rail joint oiler embodying therein a frame member, a valve casing supported thereon, a nozzle head mounted on the valve casing for a swinging movement in the plane 55 of the frame member, means for swinging said nozzle into operative position, a rock shaft extending transversely of the frame member, lever actuated means on the frame 60 for rocking said shaft, a sprocket rotative with the shaft and a chain connecting said sprocket and nozzle head.

55 7. A rail joint oiler embodying therein a frame member, a valve casing supported thereon, a nozzle head mounted on the valve casing for a swinging movement in the plane 65 of the frame member, means for swinging said nozzle into operative position, a rock shaft extending transversely of the frame member, a pinion on said shaft, a segmental gear pivoted on the frame and meshing with 70 said pinion, said segment including a lever and detent, a quadrant on the frame to be 75 engaged by the detent, a winding gear on

said rock shaft, and a flexible member connecting said winding gear and said nozzle head.

8. A rail joint oiler embodying therein, a frame member, a valve casing mounted on the frame member, a nozzle head mounted on 70 said casing for swinging movement parallel with the frame from an operative to an inoperative position and vice versa, means normally acting to swing the nozzle head into operative position, an adjustable stop carried by the valve casing and adapted to be engaged by the nozzle head to determine its angularity when in operative position, a manually operable rock shaft mounted on 75 and extending transversely of the frame member, a winding gear on said shaft and a flexible member connecting said winding gear with the nozzle head for swinging it into its inoperative position, said winding gear being angularly adjustable on the rock shaft, to compensate for changes in adjustment of 80 said stop.

9. A rail joint oiler embodying therein, a frame member, a valve casing fixed to but 85 capable of a lateral adjustment with respect to said frame member, a nozzle head mounted on the casing for a swinging movement parallel to the frame from an operative to an inoperative position and vice versa, means 90 supported by the casing for swinging the nozzle head into operative position, a manually operable rock shaft extending transversely of said frame member, a winding gear rotative with the rock shaft a flexible 95 member connecting the nozzle head and winding gear which winding gear may be shifted on the rock shaft to accommodate the lateral adjustment of said valve casing.

10. A rail joint oiler embodying therein, a frame member, an electro-magnetic valve casing supported thereon, a nozzle connected to 100 said casing for a swinging movement parallel with the frame member, contactor means supported on the frame for a swinging movement transversely of the same toward and away from, a rail, said contactor means controlling the operation of said electro-magnetic valve, a rock shaft extending transversely of the frame, means connecting the 110 said rock shaft and nozzle head for swinging said nozzle head in one direction, a lever for actuating said rock shaft and means connecting said contactor means with said lever.

11. A rail joint oiler embodying therein a frame member, an electro-magnetic casing supported thereon, a nozzle connected to said casing for a swinging movement parallel with the frame member, contactor means supported on the frame for a swinging movement transversely of the same toward and away from a rail, said contactor means controlling the operation of said electro-magnetic valve, a rock shaft extending trans- 125 130

versely of the frame, means connecting said rock shaft and nozzle head for swinging said nozzle head in one direction, a segmental member journalled on the frame parallel with the rock shaft, a flexible member connecting said segment and contactor means, a lever for rocking said shaft and means connecting said lever and segment.

12. A rail joint oiler embodying therein, 10 a frame member, an electro-magnetic valve casing supported thereby, a nozzle head connected to the frame member for a swinging movement parallel with said frame member, a contactor arm pivoted to the frame for a 15 swinging movement transversely thereof toward and away from a rail, said contactor arm including a roller for rolling engagement, with said rail and a contact finger to engage the joint plate to energize and de- 20 energize said valve and means for adjusting the position of said roller longitudinally of said arm.

13. A rail joint oiler embodying therein, a frame member, an electro-magnetic valve 25 casing supported thereby, a nozzle head connected to the frame member for a swinging movement parallel with said frame member, a contactor arm pivoted to the frame for a 30 swinging movement transversely thereof toward and away from a rail, said contactor arm including a roller for rolling engagement with said rail and a contact finger to engage the joint plate to energize and de- 35 energize said valve, and means for lengthening or shortening said contactor arm.

14. A rail joint oiler embodying therein a frame, a valve casing operatively supported thereon, a nozzle head connected to the valve casing for a swinging movement and 40 having nozzle openings, means normally acting to swing the nozzle head into operative relation with respect to the rail, and adjustable means supported by the valve casing and adapted to be engaged by a part of the nozzle 45 head for determining the angularity of the nozzle head when in said operative relation and the position of the nozzle openings with respect to rails of different heights.

15. A rail joint oiler embodying therein 50 a frame, a valve casing operatively supported thereon, a nozzle head connected to the valve casing for a swinging movement and having nozzle openings, means normally acting 55 to swing the nozzle head into operative relation with respect to the rail, and a threaded member adjustably supported by the valve casing and adapted to be engaged by a part of the nozzle head for determining the angularity of the nozzle head when in said operative 60 relation and the position of the nozzle openings with respect to rails of different heights.

16. A rail joint oiler embodying therein a 65 frame, a valve casing operatively supported

thereon, a nozzle head connected to the valve casing for a swinging movement and having nozzle openings therein, a bracket supported by the valve casing, spring means connecting the bracket and nozzle head for normally 70 swinging it into operative relation with respect to the rail, and means on said bracket providing an adjustable stop against which the nozzle head is adapted to engage when in said operative relation, whereby the nozzle 75 openings may be positioned with respect to rails of different heights.

17. A rail joint oiler embodying therein a frame, a valve casing supported on said frame, a nozzle head connected to said casing 80 for a swinging movement toward and away from the rail, said nozzle head comprising laterally spaced arms and a member connecting the same, a bracket fixed to said valve casing, springs connecting said bracket and 85 nozzle head arms and normally acting to swing them into operative relation with respect to the rail and a screw threaded member arranged in said bracket between said springs and adapted to be engaged by the 90 member connecting the laterally spaced arms of the nozzle head to act as an adjustable stop for the same.

18. A rail joint oiler embodying therein a frame member, a valve casing supported 95 thereon, a nozzle head swingably connected to the valve casing for movement into and out of operative position with respect to a rail, a valve in said casing for controlling the discharge of fluid through said nozzle 100 head, a longitudinal shaft journalled on said frame member, a sleeve member on said shaft, a contactor arm, one end of said contactor arm and said sleeve member having inter-engaging parts permitting a shortening and 105 lengthening of said arm and a device on the other end of said arm operable upon engagement with a projection on the rail to actuate the valve to permit a discharge of fluid through the nozzle head.

19. A rail joint oiler embodying therein a frame member, a valve casing supported thereon, a nozzle head swingably connected to the valve casing for movement into and out of operative position with respect to a rail, a valve in said casing for controlling the discharge of fluid through said nozzle head, a longitudinal shaft journalled on said frame member, a bifurcated member on said shaft, a contactor arm, means providing a slot and bolt adjustable connection between said bifurcated member and one end of the contactor arm and a device carried by the contactor arm and operable upon engagement with a projection on the rail to actuate the valve to permit a discharge of fluid through the nozzle head.

20. A rail joint oiler embodying therein a frame member, an electric magnetic valve casing supported by said frame member, a 130

nozzle head connected to said casing for a swinging movement in the plane of said frame, pairs of brackets on said frame, disposed with one pair forwardly and the other pair rearwardly of the valve casing, each bracket having sets of openings therein, with one set arranged parallel with the frame, and with the other set arranged transversely of the frame, a longitudinal shaft disposed in the longitudinal openings in one pair of brackets, a transverse shaft in the transverse opening in one of the brackets of the other pair, means for controlling the operation of said valve including a contact carrying arm on the longitudinal shaft and swingable thereon toward and away from the associated rail, and means operatively connecting said transverse shaft with said nozzle for swinging it into and out of operative position with respect to said rail, said first mentioned shaft being transferable from the associated openings in said first mentioned pair of brackets to the longitudinal openings in the second pair of brackets, and the transverse shaft being transferable from its opening in one of the brackets in said other pair of brackets, to a transverse opening in one of the brackets of the first mentioned pair, thus permitting the changing of said shafts and associated parts, from front to rear of said valve casing and vice versa.

In testimony whereof, I have hereunto set my hand, this 15 day of February, 1927.

HARRY W. PROTZELLER.
